UNITED STATES PATENT OFFICE.

JOSEPH T. GORDON, OF NEW YORK, N. Y.

TOY.

Application filed December 17, 1920. Serial No. 431,315.

To all whom it may concern:

Be it known that I, JOSEPH T. GORDON, a citizen of the United States, residing at New York city, in the county of New York and State of New York, have invented certain new and useful Improvements in Toys, of which the following is a specification, reference being had therein to the accompanying drawing.

10 My invention relates to improvements in toys, and has particular reference to an automatically operated toy boat with figures carrying oars to propel the boat along.

In the accompanying drawing, I have illustrated in side elevation, partly in longitudinal section, a suitable form of toy boat with the figures in position showing an embodiment of my invention.

15 1 indicates the canoe, and 2-3 the figures therein. 4 indicates a suitable form of spring motor for rotating the spindle 5 upon which is eccentrically mounted the drum 6 having a shank 7 passing through the levers 8-9. 10 indicates another lever resting upon the top of the shank 7 and provided with a transverse slot through which the pin 11 projects.

20 From the foregoing it will be observed that as the motor 4 rotates the vertical shaft 5, the eccentrically mounted drum 6 will cause the levers 8-9 to reciprocate longitudinally, first to the left, then to the right, etc., while at the same time the upper lever 10 will also have a slighter longitudinal reciprocation due to the rotation of the pin 11 in the slot of the lever 10, the movement of the lever 10 being slightly out of step from the movement of the levers 8-9.

25 The lever 10 at the left extremity is connected to the lever 12 pivoted at 13 and having a bifurcated end engaging a pin in the link 14 upon the pin 16 upon which the arm 17 is mounted. The same general arrangement is carried out with reference to figure 3. The lever 8 is also pivotally con-

nected to a lever 18 also provided with a bifurcated end engaging a pin in a link similar to 14 on the other side for operating the arm 19, and a similar set of connections is provided for the other figure 3. In the hands of the figures, suitable paddles such as 20 may be provided as shown, from which it will be observed that as the motor turns the arms will lift and reciprocate the paddles in a very natural manner causing the boat to progress as if paddled by hand.

30 Of course it will be understood that various modifications may be made in the construction and arrangement of parts without departing from the spirit of the invention as claimed.

I claim:

1. In a device of the class described, a pair of figures in a boat-like structure, a motor within said boat-like structure between said figures, an eccentrically mounted drum driven by said motor and a lever to one arm of each figure from said drum, another lever pivotally mounted upon said eccentric drum and pivotally connected to the other arm of each of said figures, the hands of said figures being provided with paddles for the propulsion of said boat.

2. In a device of the class described, a pair of figures in a boat-like structure, a motor within said boat-like structure between said figures, an eccentrically mounted drum driven by said motor and a lever to one arm of each figure from said drum, another lever pivotally mounted upon said eccentric drum and pivotally connected to the other arm of each of said figures, the hands of said figures being provided with paddles for the propulsion of said boat, the connections between said arms of said figures and said levers being pivoted levers extending upwardly through the bodies of said figures.

35 In testimony whereof I hereunto affix my signature.

JOSEPH T. GORDON.
